UNITED STATES PATENT OFFICE.

FRANK C. STUCKEL, OF RACINE, WISCONSIN, ASSIGNOR TO THE J. I. CASE THRESHING MACHINE COMPANY, OF SAME PLACE.

AUTOMATIC WEIGHER.

SPECIFICATION forming part of Letters Patent No. 634,375, dated October 3, 1899.

Application filed July 31, 1899. Serial No. 725,563. (No model.)

To all whom it may concern:

Be it known that I, FRANK C. STUCKEL, a resident of the city and county of Racine, State of Wisconsin, have invented certain new and useful Improvements in Automatic Weighers, of which the following is hereby declared to be a full, clear, and exact description.

The invention relates to apparatus especially suited for weighing wheat, clover, or other granular material, the design being to provide, as in earlier devices of this sort, an open bucket or receiver pivotally hung in counterpoise like a steelyard. Successive charges freely flow into the open mouth of the bucket; but when the load attains a given weight the bucket overbalances and slightly shifts, releasing thereby the intermediate mechanism, which promptly shuts off any further inflow and opens the bucket-bottom to let the load fall. As the bucket rises again under influence of its counterpoise the weighed load has dropped out, the bucket-bottom closes, and the shut-off gate no longer obstructs the entry of the next succeeding charge.

The present improvements are directed to the intermediate mechanism coacting with the counterpoised bucket for automatically admitting, weighing, and discharging separate portions of material.

The exact nature of the invention will appear in detail from the description following and be pointed out by the claims at its conclusion.

On the drawings like parts bear like designation throughout.

Figure 1 is a side view showing the weigher-bucket at normal position suspended in counterpoise beneath the outlet-spout of a threshing-machine elevator; Fig. 1^a, a detail plan at the fulcrum-mounts for the weigher-bucket. Fig. 2 is a view in cross-section on line 2 of Fig. 1. Fig. 2^a is a plan; Fig. 3, a detail longitudinal section view of the master-shaft and its adjuncts; Fig. 3^a, a detail longitudinal section view of the bucket and elevator-spout; Fig. 3^b, a perspective view of the worm-pinion on the master-shaft; Fig. 3^c, a perspective view of the bearing-plate for the cross-axle and worm-pinion.

The elevator-tubes A fasten above to head

102, having removable crown 103 for ready access and side outlet-spout 104 through which the grain escapes. The upper sprocket 55 for the elevator-chain is supported as usual on cross-axle D, Fig. 1, which journals in slotted bearing-plates D², Figs. 1 and 3^c, adjustably secured by bolts at opposite sides of head 102. On shifting plates D², by aid of set-screws D³, the slack in the elevator-chain is taken up or modified. Cross-axle D is constantly driven through the medium of a chain-wheel at its outer terminal or by other suitable means and carries the worm-wheel E, 65 which always revolves with the axle.

Extended lengthwise near the top of the elevator is the master-shaft G, mounted in bearings H at the plates D², Figs. 1 and 3^c, and in lower bearings H', secured to elevator-tube A. United by spline or like joint to the shaft G is a mutilated worm-pinion F, meshing at intervals with worm-wheel E on cross-axle D. Pinion F is received between the upper bearings H for the master-shaft 75 and has a suitable delay-surface thereon of width sufficient to allow worm-wheel E to clear and revolve without affecting pinion F, which latter remains at a standstill unless it be first shifted slightly to reengage. 80

Weighing-bucket B is hung beneath the outlet-spout 104 by means of the cross-yoke b, fulcrumed, as usual, at d to the opposite edges of the spout and furnished on one side with the graduated scale-beam c. Side bails 85 e' e², fastened to the bucket, afford fulcrum-seats e for pivotally suspending the bucket from cross-yoke b. A valve h, curved to conform to the bucket sides, is sustained by hangers h' at pivots h² and serves to close the open bottom of the bucket. The valve is slightly overhung with reference to pivots h², so that it tends always to swing shut into contact with stop h³, thus keeping the bucket-bottom closed even against the weight of the 95 accumulating load.

Resting over a pin i, carried by one of the hangers h', is a slotted pitman k, which at its opposite end is pivotally joined by bolt or like fastener to the radius-arm J, secured at 100 the lower terminal of master-shaft G. When said shaft begins to revolve, radius-arm J shifts pitman k, but owing to the slot therein pin i remains unaffected until the lost motion

is taken up. Thereupon the pitman pushes against pin *i*, thus swinging hanger *h'* and with it the valve *h* to unclose the bucket-bottom and discharge the load. At such junction shaft *G*, with radius-arm *J*, has described about a one-half revolution. During the further traverse radius-arm *J* gradually restores pitman *k* to normal position, the hanger *h'* at pin *i* bearing against the slot end of the pitman and retreating with it by reason of the overhung weight of valve *h*. The valve is finally checked by stop *h*³, completely shutting the bucket-bottom, while the pitman proceeds for a slight distance farther, denoted by the length of its slot, and then comes temporarily at rest to await the discharge of the next load.

At its upper end the longitudinal master-shaft *G* carries the radius-arm *I*, united by simple chain *O* or other flexible connection with the bell-crank terminal *m* of the yoke-like gate *k'*, pivoted, as at *l*, on the sides of the elevator-head and serving at intervals to close the exit-spout for the grain. Gate *k'* is made sufficiently heavy not only to shift terminal *m* and take up the slack in chain *O*, but also to impart through the chain a slight initial movement at intervals to radius-arm *I*, and in consequence to master-shaft *G*, if permitted. Ordinarily a dog or stop-block *g*, carried by the master-shaft near its mid-length, Figs. 1 and 3, encounters a trip *f*, projected, as shown, from bucket *B*, and retains the shaft at a standstill despite the weight of spout-gate *k'*. Once the bucket is loaded it promptly overbalances the scale-beam and turns down far enough about fulcrum *d* for trip *f* to clear stop-block *g*. Master-shaft *G* thus stands released and experiences a minor impulse forward due to the weight of gate *k'*, imparted through terminal *m* and chain *O* to radius-arm *I*. Simultaneously gate *k'* begins to lower and will persist in its course to the extent permitted by the slack of chain *O*. Owing to the difference in radius, reckoned from common center *l*, the gate *k'* will describe quite a long path while terminal *m* is moving over a comparatively slight distance. A meager shift of the terminal suffices to bring gate *k'* at rest across the spout 104, shutting off any further inflow of grain to the bucket. The minor impulse forward experienced by master-shaft *G* through gate *k'* suffices to turn pinion *F* until its initial tooth encounters the rapidly-rotating worm *E*. The two parts are at once in mesh, and shaft *G* thereupon proceeds to describe a single revolution. At the outset of its movement shaft *G* completes the lowering of gate *k'*. Chain *O* remains slack for perhaps one-half revolution of shaft *G*, and when it finally hauls taut the chain begins to raise the gate *k'*, say, during the last quarter-turn of the shaft. At such stage the pitman *k* has not only opened the bucket-bottom, but is proceeding to close it again. The movements of the spout-gate and the bucket-bottom are readily timed and be-

sides are very rapid, so that practically the bucket receives no late excess and loses no premature surplus grain. When the bottom valve *h* begins to open, the bucket-weight is at once lessened and the counterpoise proceeds to lift the bucket to normal position. This movement restores trip *f* to the path of stop *g*, which stop it promptly encounters at the end of the single revolution of shaft *G*. The delay-surface of pinion *F* enables said pinion to disengage from worm-wheel *E*, while the encounter of stops *f* *g* at once brings shaft *G* to a standstill. A pintle 200 on the upper face of trip *f* plays through a hole in guide-plate 201, secured to the elevator-head. The pintle 200 coacts with link 202, extended between the bucket and the elevator-tube to prevent the bucket from swaying as it moves up and down.

Radius-arms *I* *J* at opposite ends of the master-shaft are offset in angular relation to each other with reference to the shaft-axis, arm *I* being given a slight "lead," so that it clears the "dead-point" just before the rotation of the shaft is arrested. In such position the arm promptly responds to the influence of the weight of gate *k'* at the beginning of the next turn. A tally of any convenient type attaches to elevator-tube *A*, and by its end wheel may engage a worm *L*, splined to revolve with shaft *G*.

Coöperating with the cross-axle for the upper sprocket of the elevator, the use of the master-shaft *G* extended lengthwise, as shown, enables said shaft to directly control both the spout-gate above and the bucket-valve below. The stop-block is carried by the shaft to encounter the trip projected from the bucket while the tally is in immediate connection with the actuating worm-wheel at the shaft. Compactness and simplicity of organization are thus assured. The vertical position of the master-shaft allows for quick readjustment of the elevator-chain, the shift of cross-axle *D* for such purpose being effected by means of the bracket-plates *D*². The spline-joint between master-shaft *G* and pinion *F* permits the readjustment to occur without disengaging the pinion from its worm-wheel *E*. The offset relation of cross-axle *D* and master-shaft *F*, due to the use of the worm-gear, enables the power-pulley to be applied at either end of axle *D*—that is, the terminal of axle *D* can be carried past the worm-gear without interference and the machine be fitted to the body of the separator at right or left hand side, as desired.

Obviously the details of structure can be varied according to the mechanic's skill without departure from the essentials of the improvement.

Having thus described my invention, what I claim as new, and desire to secure by Letters Patent, is—

1. In automatic weighers, the combination with the outlet-spout and its control-gate at the elevator-head, of the weigher-bucket hung

- in counterpoise beneath said spout and having a valved bottom thereon, the upper cross-axle for the endless belt carried upon the elevator-casing and furnished with an outer worm - wheel, the master - shaft extended lengthwise outside of the elevator in angular relation to the cross-axle and provided with upper and lower connections leading thence to the spout-gate and to the bucket-valve respectively, the mutilated worm-pinion mounted upon the master-shaft and driven intermittently from said worm-wheel, suitable means for giving an initial partial rotation to the master-shaft, a trip-off at the bucket and a stop on said shaft governed thereby, substantially as described.
2. In automatic weighers, the combination with the outlet-spout and its control-gate at the elevator-head, of the weigher-bucket hung in counterpoise beneath said spout and having a valved bottom thereon, the upper cross-axle for the endless belt carried in side bearing-plates and furnished with an outer gear-wheel, the master-shaft sustained lengthwise of the elevator having a pinion thereon carried by the bearing-plate of the cross-axle and intermittently engaging the gear-wheel thereof, proper connections extended from the master-shaft to govern the spout-gate and the bucket-discharge respectively, suitable means for giving an initial partial rotation to the master-shaft, a trip-off at the bucket and a stop on the master-shaft controlled thereby, substantially as described.
3. In automatic weighers, the combination with the outlet-spout and its control-gate at the elevator-head, of the weigher-bucket hung in counterpoise beneath said spout and having a valved bottom thereon, the upper cross-axle for the endless belt carried upon the elevator-casing and furnished with an outer gear-wheel, the master-shaft extended lengthwise outside of the elevator in angular relation to the cross-axle and provided with upper and lower terminal connections joined to the spout-gate and to the bucket-bottom valve, respectively, the independent mutilated pinion separately mounted at intermediate position upon said master-shaft and driven intermittently from the gear-wheel, suitable means for giving an initial partial rotation to the master-shaft, a trip-off at the bucket and a stop on said shaft governed thereby, substantially as described.
